UNITED STATES PATENT OFFICE.

LESLIE H. BURLIN, OF CHICAGO, ILLINOIS, ASSIGNOR TO BURLIN CO., A FIRM COMPOSED OF LESLIE H. BURLIN AND WALTER H. SEDGWICK, OF CHICAGO, ILLINOIS.

DESIGN FOR A BASE FOR SMOKER STANDS OR SIMILAR ARTICLE.

Application filed August 8, 1925. Serial No. 14,349. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for a Base for Smoker Stands or Similar Article, of which the following is a specification, reference being had to the accompanying drawing, forming a part thereof.

The Fig. 1, is a plan view and Fig. 2, is a side elevation of a base for smoker stands or similar article showing my new design.

My base for smoker stands or similar article is made and sold as a complete and separate article of manufacture.

I claim:

The ornamental design for a base for smoker stands or similar article, as shown.

LESLIE H. BURLIN.
